Patented June 12, 1923.

UNITED STATES PATENT OFFICE.

JUSTIN FIZESÁN, OF SAUGERTIES, NEW YORK.

AUTOMATIC SHIP-STEERING MECHANISM.

Application filed April 18, 1922. Serial No. 555,147.

To all whom it may concern:

Be it known that I, JUSTIN FIZESÁN, a citizen of Yugoslavia, residing at Saugerties, in the county of Ulster and State of New York, have invented certain new and useful Improvements in Automatic Ship-Steering Mechanism, of which the following is a specification.

This invention relates to operating mechanism for ships' rudders and it has for one object to provide a simple form of power mechanism for operating a ship's rudder.

A further object is to provide an indicating device located in the pilot house, for showing the angular position of the rudder.

Another object relates to the provision of a hand operating means capable of operating through the same connecting elements as the power mechanism in the event of disabling of the latter.

For further comprehension of the invention, and of the objects and advantages thereof, reference will be had to the following description and accompanying drawings, and to the appended claims in which the various novel features of the invention are more particularly set forth.

Fig. 1 of the drawings is a plan view showing my improved steering mechanism applied to a ship.

Fig. 2 is a partial enlarged longitudinal vertical sectional view of the steering mechanism, taken along the line 2—2 of Fig. 1.

Fig. 3 is a detail front elevational view, showing particularly the drive mechanism.

Fig. 4 is a detail transverse vertical section on the line 4—4 of Fig. 2.

Fig. 5 is a plan view of one of the winding drums.

In Fig. 1 of the drawings I have indicated a ship in general outline at 10, the rudder being shown at 11, being adapted for operation by means of an arm 12 fixed to the upper end of the rudder post 13, which extends into the over-hanging stern of the hull in the usual manner. Connected to the rudder arm 12 are ropes 15 extending laterally around pulleys 16 and then forwardly to connect to drums 17 fixed on a transverse shaft 18. These drums 17 as shown vary in diameter from end to end and are formed with grooves 19 in which the ropes are localized. The object of this construction is to compensate for different relative movements of the two ropes as one pulls

on the rudder arm and the other is pulled thereby.

Fixed on the shaft 18 is a worm gear 21 engaged by a worm pinion 22 fixed on the rear end of a longitudinal shaft 23 which has a bevel gear 24 fixed on its front end. This gear 24 is engaged on opposite sides by a pair of bevel gears 25 each loose but not axially movable on a transverse shaft 26. This shaft 26 is driven from a constantly rotating shaft 27 (see Fig. 3) which may be driven in any suitable manner, the connections between the shafts 26 and 27 comprising the bevel gears 28 and 29 fixed on opposite ends of a vertical shaft 30 and engaging gears 31 and 32 on the shafts 26 and 27.

The gears 25 may be individually rotatably engaged with the shaft 26 by means of a clutch sleeve 35 feathered on the shaft 26 and adapted to engage clutch faces 36 on the gears. The sleeve 35 is shifted by a lever arm 37 fixed on a rock-shaft 38 which extends rearwardly and is adapted to be manually rocked. As here shown a clutch element 39 is fixed on the rear end of the rock-shaft 38 and is engaged by one end of a double ended clutch sleeve 40 fixed on a steersman's wheel 41 loose on shaft 38. Adjacent the opposite end of the clutch sleeve 40 is a second clutch element 42 loose, but not axially movable on shaft 38, an expansion spring 43, coiled around shaft 38, normally holding the clutch sleeve 40 in engagement with the clutch element 39. Fixed to clutch element 42 is a small sprocket 44 connected by a chain 45 with a large sprocket wheel 46 on the shaft 23. As will be apparent, if necessary the rudder can be operated by hand by pushing the wheel 41 forward until its clutch sleeve 40 engages with the clutch element 42.

I also preferably provide an indicating device which shows the angular positioning of the rudder 11. This device here comprises a pointer 50 adapted to swing across a scale 51 and being fixed on a stub shaft 52 on which is also fixed a large sprocket wheel 53 connected by a chain 54 with a small sprocket wheel 55 to which is co-axially fixed a bevel gear 56 meshing with a pinion 57 on a short vertical shaft 58 on which is a worm gear 59 engaging a worm pinion 60 fixed on shaft 23. It will of course be understood that the reducing gearing above described is pro-

portioned so as to cause the pointer 50 to swing in correspondence to the rudder 11. The wheel 41 and pointer 50 will be suitably positioned in the pilot house, indicated at 5 65, of the ship.

While I have illustrated and described a preferred embodiment of my invention it is to be understood that I do not limit myself to the precise construction here shown, and 10 that various changes and modifications might be made therein without departing from the spirit and scope of the invention as defined in the appended claims.

Having thus described my invention what 15 I claim as new and desire to protect by Letters Patent of the United States is as follows:

1. In combination with a rudder, a rotatable shaft operatively connected thereto, 20 power mechanism for rotating said shaft in opposite directions, control means therefor including a clutch element, an arm adapted to shift said clutch element, a rock-shaft on which said arm is fixed, a pair of clutch elements one of which is fixed and one loose on 25

said rock-shaft, a clutch sleeve loose on said shaft between said clutch elements, a steersman's wheel fixed on said clutch sleeve, and means forming an operative connection between said loose clutch element and said first 30 mentioned shaft.

2. In combination with a rudder, a rotatable shaft operatively connected thereto, a power mechanism for rotating said shaft in opposite directions, control means therefor 35 including a clutch element, an arm adapted to shift said clutch element, a rock-shaft on which said arm is fixed, a pair of clutch elements one of which is fixed and one loose on said rock-shaft, a clutch sleeve loose on said 40 shaft between said clutch elements, a steersman's wheel fixed on said clutch sleeve, and means forming an operative connection between said loose clutch element and said first mentioned shaft, and a spring normally 45 holding said clutch sleeve in engagement with said fixed clutch element.

In testimony whereof I have affixed my signature.

JUSTIN FIZESAN.
